Attorney

UNITED STATES PATENT OFFICE.

WILLIAM DAVID ORA MILLER, OF MACKSVILLE, KANSAS.

RATCHET WRENCH.

Application filed December 7, 1925. Serial No. 73,728.

My present invention pertains to ratchet wrenches, and contemplates the provision of a ratchet wrench characterized by the capacity to yieldingly hold and prevent dropping or casual displacement of the article or articles that are being turned through the medium of the wrench.

My novel wrench is designed more especially for holding in detachable manner and turning a washer and nut employed in a certain special relation, all of which will be hereinafter fully described.

To the attainment of the foregoing my invention consists in the improvement as hereinafter described and definitely claimed

In the accompanying drawings, forming part of this specification:—

Figure 1 is side elevation illustrating my novel wrench and also illustrating a nut held in the wrench.

Figure 2 is a view partly in side elevation and partly in section, showing a washer in my novel wrench.

Figure 3 is a fragmentary longitudinal central section showing both parts of my improvement.

Figure 4 is a detail perspective, on an enlarged scale, illustrative of the shoe comprised in my invention and designed especially for yieldingly holding a washer.

Figure 5 is an enlarged detail section showing the spring element for contacting with and yieldingly holding the nut referred to.

Similar numerals of reference designate corresponding parts in all of the views of the drawings.

Without affecting my invention the body 1 of the wrench may be of the construction illustrated or of any other appropriate construction. At 2 the said body is equipped with a pawl, under the influence of a flat spring 3. One end portion of the body 1 is accommodated for the reception and rotation of the rotary ratchet member 4 of the wrench, the said ratchet member 4 being provided with peripheral teeth 5.

My improvements are carried by the said rotary ratchet member 4 which in general is of annular form. Interiorly a portion of the member 4 is shaped to receive a hexagonal nut designated by 6. In other words the said portion of the member 4 is interiorly of hexagonal form so as to receive the

nut 6, and so as to assure turning of the nut 6 when the member 4 is turned. Another portion of the member 4 is designed to receive and yieldingly hold a washer 7, the said portion being designated by 8, as shown in Figure 5, while the nut receiving portion is 60 designated by 9 in the same figure. For the holding of the nut 6, the portion 9 of the rotary member 4 is provided with a spring strip 10, the said spring strip 10 having its major portion 11 disposed within the annular part 9 of the member 4 so as to contact with the side of the nut, and also having hooked portions 11 engaging the edges of the annular portion 9 as clearly brought out in Figure 5. The said spring strip 10 is 70 also clearly shown in Figure 3 and in Figures 1 and 2. The portion 8 of the member 4 is also of general annular form, and for the holding of the washer 7, the annulus of the portion 8 is partly formed by an arcuate shoe 12, movable relative to the remainder of the annulus. The said shoe 12 is subject to the influence of a curvilinear spring 13, Figures 1 and 3, the said spring 13 hugging the shoe 12, and being connected at 14 to the 75 portion 8 and having its opposite end arranged flush with the end of the major portion of the shoe 12 and appropriately secured to the shoe 12 at the latter end. The shoe 12 is provided with reduced end portions 15 lapped with the contiguous end portions of the remainder of the portion 8, and by virtue of the described arrangement of the curvilinear spring 13 it will be manifest that the shoe 12 will be pressed yieldingly inward so that the shoe will exert frictional contact on the perimeter of the washer with the result that there is little or no liability of the washer accidentally dropping from the portion 8 of the rotary member 4.

In the practical use of my novel wrench it will be manifest that the strip 10 while adapted to preclude accidental dropping of the nut from the portion 9 of the member 4 will not interfere in any measure with the ready placing of the nut in the same portion 9 and will not interfere in any measure with the nut being positively turned through the medium of the portion 9. It will also be manifest that in no measure will the spring-pressed shoe 12 interfere with the placing of the washer in the portion 8 of the

rotary member 4 nor with the turning of the washer with the nut, the nut and the washer being keyed together in furtherance of the special purpose to which the nut and washer are put.

It will be further manifest that notwithstanding the capacity of function ascribed to the improved portions of the member 4, the said improved portions do not materially increase the cost of the rotary member 4 of the wrench or of the wrench considered as a whole.

My improved wrench is designed more particularly for holding and turning the nuts of transmission band adjustment and the washers or lock washers complementary to said nuts, this with a view to preventing the nuts and washers from dropping into the transmission case of a well known type 20 of automobile.

In the new model of the said well known type of automobiles, the transmission bands are removed through the opening left by the removal of a transmission cover plate, the band being removed through the said opening on the following operation. The transmission bands adjusting nuts and washers are first removed, the transmission pedal shafts are then pulled out, and thereupon the transmission bands are removed. Manifestly incident to the operation described, my novel wrench may be used to advantage for turning off and removing the nuts and washers, and after the said removal, my novel wrench is utilized as a means for holding the nuts and washers and for the removal of the nuts and washers from the transmission case without liability of the nuts or washers being accidentally dropped into said case. Again it will be appreciated that my novel wrench may be used to advantage in introducing the nuts and washers and positioning the same, there being no liability in either use of the wrench of the nuts and washers accidentally leaving the wrench, and yet manifestly the wrench may be easily disengaged to leave the nuts and washers in working position, and when the nuts and washers are removed through the medium of the wrench, the nuts and washers may be expeditiously and easily removed by slight pressure from the wrench.

It will be appreciated from the foregoing that notwithstanding my improvements increase the efficiency of the wrench to a material extent, the improvements do not increase the size of the wrench or render the same cumbersome, and it will also be appreciated that the improvements are so relatively arranged that they are not liable to get out of order and hence the wrench with my improvements is as well adapted to withstand the usage to which ratchet

wrenches are put as an ordinary ratchet wrench.

65

I have specifically described the construction and relative arrangement of the parts embraced in the present and preferred embodiment of my invention in order to impart a full, clear and exact understanding 70 of the same embodiment. I do not desire, however, to be understood as confining myself to the construction and arrangement of parts as disclosed, my invention being defined by my appended claims within the 75 scope of which structural changes and changes in arrangement may be made without departure from my invention.

Having described my invention, what I claim and desire to secure by Letters-Patent, 80 is:—

1. A wrench having a handle and a member with an annular washer receiving portion and a nut receiving portion, and also having a segment forming a part of the said 85 annular portion and adapted to yieldingly hold a washer therein; and spring means pressing said segment.

2. A wrench having a handle and also having a member with an annular washer receiving portion and a nut receiving portion, and with a segmental shoe forming a part of said annular portion and adapted to contact with and yieldingly hold a washer in the portion, and spring means pressing 95 said segment.

3. A wrench having a handle and also having a member with an annular washer receiving portion and a nut receiving portion, said annular portion having a segmental shoe forming a part thereof and adapted to contact with and yieldingly hold a washer in the portion and a spring pressing said segmental shoe; the said segmental shoe having reduced end portions arranged in 105 lapped relation to the ends of the rest of the annular washer-receiving portion, and the spring being of curvilinear form and connected at one end to the annular portion and hugging the shoe and arranged to yieldingly press the said shoe inwardly.

4. A ratchet wrench, having a handle and a member including a nut receiving portion and a washer receiving portion; a spring strip arranged in the nut receiving portion and having hook ends engaging the edges of the said portion; a segmental shoe forming part of the washer receiving portion and engaged therewith and movable relative thereto, and a spring of curvilinear form connected at one end to the said washer receiving portion and hugging the shoe and arranged to yieldingly press the shoe inwardly.

In testimony whereof I affix my signature.
WILLIAM DAVID ORA MILLER.
